1 Claim. (Cl. 28—43)

This invention relates to improved apparatus for separating single threads from thread layers that have been leased to prevent the crossing or inversion of two consecutive threads. The apparatus is particularly suitable for use in conjunction with knotting machines wherein the threads of an exhausted layer are to be tied to the threads of a new layer.

The primary object of the present invention is to provide an improved, inexpensive, simple and durable apparatus for separating single threads from a thread lease. The invention is characterized by the use of separator or shaker means for loosening the threads of the lease, said shaker means being also operable in combination with fork pusher means and finger means to separate single threads from the lease.

Other objects and advantages of the invention will become apparent from a study of the following specification when considered in conjunction with the accompanying drawing, in which:

FIGURE 1 is a somewhat schematic side elevational view of the thread separating apparatus with certain parts removed for the sake of clarity;

FIGURES 2 and 3 are schematic vertical transverse and plan views, respectively, of the apparatus of FIGURE 1; and

FIGURES 4-7 are schematic illustrations of the operation of the apparatus to remove successive single threads from the lease.

Referring to FIGURES 1-3, the apparatus includes an axially reciprocating and oscillatory fork 1 that is arranged between and parallel with a pair of pipes or tubes 2 that contain lease cords 9, and a pair of rotary separator or shaker elements 3 the ends of which are provided with leaves 4. The axes of the fork, pipes and rotary elements are parallel and are arranged in a common horizontal plane. Arranged above, and in the vertical plane containing, fork 1 is a rocker arm 5 that pivots about a fixed horizontal axis (as shown by the solid and phantom lines in FIGURE 1). Pivotaly connected with the free end of arm 5 is a finger 6 which is operable to separate successive end threads from the lease 7 as will be described below.

The fork 1 oscillates about its longitudinal axis between first and second angular positions corresponding with the angular positions of the thread slants in the lease (as shown in FIGURES 6a and 7a, respectively). The fork 1 is also forwardly and rearwardly reciprocable between first and second longitudinally displaced positions (as shown in FIGURES 3 and 7, respectively) in which the extremities of the bifurcated end portion of the fork push against and are retracted from the lease threads, respectively.

The pipes 2 continuously extend into the lease beyond the separator elements 3 and the fork 1 and serve to maintain open the lease thread layers and to prevent the lease cords 9 from bending or from obstructing the operation of the other elements.

As shown in FIGURES 4 and 7, when the fork 1 is in the retracted position, the leaves 4 of the separator elements 3 extend into the lease. The rotating elements 3 and the leaves 4 cause shaking (or loosening) of the lease threads adjacent the fork 1.

2

Referring to FIGURE 1, it will be seen that finger 6 is continuously biased in the clockwise direction relative to arm 5 by a spring 12. As the arm 5 pivots downwardly to the position shown by the phantom lines, an extension on finger 6 engages stop block 13, whereupon the finger 6 is pivoted in the clockwise direction relative to arm 5 to the position illustrated in phantom in FIGURE 3.

The operation of the thread separating apparatus may now be described with reference to FIGURES 4-7, it being remembered that the apparatus works in conjunction with a knotting machine (not shown) that moves between two leased thread layers at a certain speed.

Referring to FIGURES 4 and 4a, assume that at a given time the first end thread 8 of the lease 7 extends over the right-hand pipe 2 and under the left-hand pipe 2. The fork 1 is in the retracted position and the leaves 4 of the rotary members 3 extend between the lease layers. As shown in FIGURES 5 and 5a, as the fork 1 is axially displaced to cause the bifurcated end to engage the thread slant extending from beneath the right-hand pipe 2 and above the left-hand pipe 2, all threads having the same slant as the fork are displaced forwardly (i.e., to the left in FIGURE 3) by the fork. Consequently, all of the threads of the opposite slant—with the sole exception of the end thread 8—are also displaced forwardly as a result of the action of the fork on the threads of the first slant. This axial movement of the fork is accompanied by rotary movement of the separators 3 to cause displacement of the leaves 4 to vertical positions that maintain the end thread 8 in place. Movement of the leaves 4 to the vertical positions causes shaking of the lease threads as they are displaced forwardly by the fork 1. The finger 6 is pivoted (by stop block 13 as arm 5 pivots downwardly) from the position shown in FIGURE 5 to the position shown in FIGURE 6, whereby the single thread 8 is displaced laterally rearwardly relative to the other lease threads. Upon the retraction of fork 1 from the FIGURE 6 position, the lease threads 7 are returned, as a result of the tension thereon, to their original FIGURE 4 position. To remove the next end thread, the fork 1 is pivoted to the opposite slant as shown in FIGURE 7a, and the operation described above is repeated.

In certain cases, the lease threads may be so delicate as to preclude the use of rotary separator members 3. In this case, the separator members are oscillated about their axes through angles of 90 degrees to effect, in combination with the fork means, separation of successive end threads from the lease. Furthermore, in certain instances it may be desirable to utilize fork means provided with four prongs instead of two.

While in accordance with the provisions of the patent statutes the preferred form and embodiment of the invention has been illustrated and described, it will be apparent to those skilled in the art that changes may be made in the apparatus described without deviating from the invention set forth in the following claims.

What is claimed is:

Apparatus for separating single threads from a lease, comprising

a pair of parallel spaced lease tubes adapted to support intercrossed lease threads in such a manner that alternate threads of the lease extend with opposite slants over and under, and under and over, said lease tubes, respectively;

a pair of parallel, spaced separator elements arranged on opposite sides of, and coplanar and parallel with, said lease tubes, each of said separator elements extending at one end between the lease thread layers and terminating in a generally planar leaf portion, said separator elements being axially rotatable to displace said leaf portions between first and second

positions parallel with and normal to the lease axis, respectively;
axially reciprocatory and oscillatory fork means arranged between, spaced from and parallel with said lease tubes, said fork means being operable to engage the end of the lease layer having a slant opposite the slant of the end thread when the separator element leaf portions are in the second position and to laterally displace the lease threads in one direction away from said end thread, said end thread being maintained against displacement in said one direction by said leaf portions; and
finger means operable to laterally displace said end thread in the opposite direction relative to said lease threads, whereby upon retraction of said fork means

from said lease threads and upon return of the lease threads to their initial position, said end thread is laterally spaced from said lease threads.
